FRANZ KRATZ, OF STUTTGART, GERMANY, ASSIGNOR, BY MESNE ASSIGNMENTS, TO
AMERICAN BOSCH MAGNETO CORPORATION, OF NEW YORK, N. Y., A CORPORATION
OF NEW YORK.

ELECTRIC SWITCH.

1,311,974.

Specification of Letters Patent. Patented Aug. 5, 1919.

Application filed April 30, 1914. Serial No. 835,347.

To all whom it may concern:

Be it known that I, FRANZ KRATZ, engineer, a subject of the Emperor of Germany, residing at and whose post-office address is 5 Stuttgart, 59^a Schloss strasse, Germany, have invented certain new and useful Improvements in Electric Switches; and I do hereby declare the following to be a full, clear, and exact description of the invention, such as 10 will enable others skilled in the art to which it appertains to make and use the same.

The present invention discloses an electric switch of large current capacity having a bridge member with contact fingers for completing the circuit between the switch studs with a strong wiping contact, and also having a circuit breaking member for interrupting the circuit between the studs, the two members being adapted to be moved in 20 a straight line by means of an operating lever fastened thereto. In the preferred form of construction, the bridge member is made up of superposed plate springs cut-out and bent to form depending contact fingers, 25 and the circuit breaking member is made up of separated spring plates carrying carbon contacts at their outer ends between the contact fingers and fastened at their central portion to the bridge member so that the 30 carbon contacts are separated from the switch studs in movements of substantial parallel translation. In this way, there is produced a cheap and easily assembled switch having a large contact surface and 35 adapted to interrupt the circuit with a quick and reliable break.

In the accompanying drawings, illustrating the preferred form of my invention,

Figure 1 is a longitudinal elevation, partly 40 in central section;

Fig. 2 is a plan view; and

Fig. 3 is a section on line 3—3 of Fig. 2.

The bridge member *a* comprises three plate springs of metal which are cut-out and 45 bent to form the four depending contact fingers *c*, with edge-on engagement with the plane or smooth contact surfaces of the switch studs or terminals *d* and *e*. Preferably the outermost plate spring of each contact finger is slightly inclined outwardly of the line perpendicular to the contact surface of the stud, and the innermost plate spring of each contact finger is slightly inclined inwardly of this line, so that during the 50

switching movements the plate springs of 55 each contact finger spread independently of each other and effect a strong wiping action on the stud, and produce a reliable and accomodating contact at each finger over a comparatively large area. 60

The circuit breaking member comprises the two plate springs *g* of metal cut-out along the lines *k* to form the arms *g* and the connecting end portions *l*. The plate springs are separated from each other by the bushing *i* and mounted directly upon the plate springs of the bridge member *a*. The two plate springs are fastened together at their outer ends by the hollow rivets *h*, which carry the carbon blocks *f* with the contact surfaces 70 thereof somewhat below the level of the contact surfaces of the fingers *c*. In this way, the carbon contacts *f* engage the studs *d* and *e* before the engagement of the contact fingers *c*, and they disengage the studs only 75 after the contact fingers are disengaged therefrom, the carbon contacts being pressed into intimate engagement with the switch studs and being disengaged therefrom in movements of substantial parallel translation, whereby the entire contact surface of each carbon block is disengaged as a whole. 80

The bridge member and the circuit breaking member are fastened together between the flanges of the sleeve *n*, the insulating bushing *o* being interposed to insulate the sleeve from the live parts of the switch. The operating lever *q* is provided with a shoulder *s*, abutting against one end of the sleeve *n*, and with an extension *t* of square cross section passing through the square central opening in the sleeve *n*. A split washer *w* is passed over the threaded end of the operating lever *q*, and the nut *r* is screwed home to reliably fasten the bridge member 95 and the circuit breaking member together, and to the operating lever. The operating lever is adapted to be moved in a straight line substantially perpendicular to the contact surfaces of the switch studs, that is, in 100 substantially the direction of the contact fingers *c*, and this movement of the operating lever may be brought about by hand in any suitable way, or by connection to the core or armature of an electromagnet. 105

Having thus described my invention, what I claim is:

In an electric switch having studs with

smooth contact faces, a conducting bridge member adapted for perpendicular switching movements relatively to said contact faces and comprising a plurality of superposed cut out and bent spring plates having forked ends with the prongs thereof extending substantially in the direction of the switching movement, and a conducting circuit breaking member having contacts at its ends between said prongs and normally projecting beyond the ends of the prongs to disengage said contact faces after the prongs are disengaged therefrom, said circuit break-

ing member comprising two separated and parallel spring plates fastened at their central portions to the bridge member so as to produce between the contacts and studs circuit breaking movements of substantially parallel translation.

In testimony whereof I affix my signature, 15
in presence of two witnesses.

FRANZ KRATZ.
